CLAIM

The ornamental design for a goal frame, as shown and described.

DESCRIPTION

FIG. 1 is a front perspective view of the goal frame, showing my new design;

FIG. 2 is a rear perspective view thereof;

FIG. 3 is a front elevation view thereof;

FIG. 4 is a rear elevation view thereof;

FIG. 5 is a left side elevation view of the goal frame, wherein the right side elevation view is a mirror image thereof;

FIG. 6 is a top plan view thereof; and,

FIG. 7 is a bottom plan view thereof.
